[57]

ABSTRACT

Negative ions are generated by passing a stream of gas and water vapour free of water droplets through a corona discharge of 5,000 volts or more.

5 Claims, 2 Drawing Figures

PATENTED AUG 27 1974

3,832,554

FIG.1.

FIG.2.

GENERATION OF NEGATIVE IONS

This invention relates to the generation of negative ions, for example hydroxyl ions.

The generation of negative ions in air has long been a desirable end in order to treat pulmonary and other respiratory conditions, for example emphysema. There have been attempts in the past to provide methods and apparatus for producing air having a high negative ion content, but all previous types of apparatus have tended to be ineffective due to the rapid recombination of the negative ions produced after leaving the negative ion production zone.

British Pat. Specifications Nos. 392,945, 414,687, 420,360 and 436,467 disclose methods and apparatus for electrically treating moist air, but the air stream produced by the apparatus in those cases, when operated as set forth in the specifications does not contain negative ions in stable form.

According to a first feature of the present invention there is provided a method of producing negative ions which comprises passing a stream of gas and water vapour not containing any water droplets through a corona discharge of voltage at least 5,000 volts.

According further to the invention, there is provided an apparatus for the production and transport of negative ions which comprises means for producing a stream of gas and water vapour not containing any water droplets, a corona discharge gap, and means for blowing the stream through the corona discharge gap and exhausting it to atmosphere.

By the use of this method, negative ions are generated which are not subjected to rapid recombination in clean dry air. In polluted air, it is found that the generator clears the pollution, for example smells or mist. The stream of negative ion containing air so produced is valuable in medical therapeutics for the treatment of pulmonary and respiratory conditions. Contrasted with previous apparatus, the present apparatus does not need to be directly in front of the mouth of the patient being treated — the negative ion-containing stream of gas is stable and recombination rates are comparatively low. The patient may accordingly be several feet away from the apparatus and yet be benefitted thereby. In time the polarity of the room and contents in which the apparatus is operated may be changed from positive to negative.

If desired, the stream of gas which is passed through the corona discharge may contain components additional to air and water vapour, and by breathing the stream of air containing negative ions, these components may be introduced into the body. The components which may be used in this way vary widely, but include elemental materials such as alkali, alkaline earth and other metals, and other chemical compounds which may be absorbed from the atmosphere by the lungs.

Naturally, it is possible to vary the strength and intensity of the corona discharge in order to vary the ionisation produced. The voltage may be raised if desired to a value much above the 5,000 volt minimum, and this is of particular use in large ion generators such as might be used to condition a treatment room or even a complete hospital ward.

The invention is described, by way of example, with reference to the accompanying drawings which show a

negative ion generator according to the invention.

In the drawings:

FIG. 1 is a side view of the apparatus, and

FIG. 2 is a top view.

5 Referring to the drawing, the apparatus comprises a standard evaporator 1 (such as that sold under the Trade Mark MOULINEX) which has been modified by the addition of extra evaporator wicks 2. These wicks may suitably be made of filtration board, and their area 10 must be sufficient to give adequate humidification. This evaporator contains a fan which sucks in air from the atmosphere and slowly passes it over the wicks and exhausts it into a convergent channel 3. Connected to the narrower end of channel 3 is a treatment tunnel 4 in the 15 centre of which is located a pair of corona discharge electrodes, a lower spike negative electrode 5 and an upper semi-cylindrical positive electrode 6. The lower electrode is mounted on a suitable high voltage generator 7, e.g., any suitable apparatus capable of producing a spike voltage of -7,500 volts. The corona discharge current in apparatus of this type is preferably 20 to 30 20 microamps.

The outlet end of tunnel 4 is connected to a discharge vent 8. In use, the evaporator 1 is filled with water, 25 preferably distilled or deionised water, and the fan set in motion. The corona discharge is set up and it is found that after a brief period of settling down, measurable negative ion concentrations may be easily detected more than 20 feet away from the apparatus.

It is desired to introduce negative ions other than OH into the exit stream of gases, then, for example, simple salts may be dissolved in the water of the evaporator, e.g., calcium salts.

The apparatus described above may be made of any convenient material such as metal, plastics or fibreglass, but the preferred material of construction is wood.

It is preferable to use an evaporator of such efficiency that, under the conditions of use, the relative humidity of the gas stream passing through the apparatus is raised by at least 5 percent.

I claim as my invention:

1. Apparatus for the production and transport of negative ions which comprises means for producing a stream of gas and water vapour not containing any water droplets, a corona discharge gap, and means for blowing the stream through the corona discharge gap and exhausting it to atmosphere.

50 2. The apparatus of claim 1 wherein the means for producing a stream of gas and water vapour includes a wick evaporator, said wick evaporator providing a large evaporative surface area from which the water evaporates to provide water vapour free of water droplets.

55 3. The apparatus of claim 1 wherein the means for producing a corona discharge gap provides a corona discharge of voltage of at least 5,000 volts.

4. The apparatus of claim 1 wherein the means for producing a corona discharge gap provides a corona discharge of voltage of at least 6,000 volts.

60 5. The apparatus of claim 1 wherein the means for producing a corona discharge gap provides a corona discharge current in the range of from 20 to 30 microamps.
